Primary Examiner — Kevin K Rudzinski*Assistant Examiner* — Kimberly Barnes(74) *Attorney, Agent, or Firm* — Kaspar Law Co., LLC;
Scott R. Kaspar(57) **CLAIM**

The ornamental design for a wall panel with octagonal-shaped mount, as shown and described.

DESCRIPTION

FIG. 1 is a back perspective view of a wall panel with octagonal-shaped mount, showing my new design.

FIG. 2 is a back view of a wall panel with octagonal-shaped mount.

FIG. 3 is a front view of a wall panel with octagonal-shaped mount.

FIG. 4 is a left side view of a wall panel with octagonal-shaped mount.

FIG. 5 is a right side view of a wall panel with octagonal-shaped mount.

FIG. 6 is a cross-sectional view of a wall panel with octagonal-shaped mount taken along line 6-6 in FIG. 2.

FIG. 7 is a top view of a wall panel with octagonal-shaped mount; and,

FIG. 8 is a bottom view of a wall panel with octagonal-shaped mount.
